F. W. BROWN

DEVICE FOR SEPARATING FRUIT JUICES FROM PULP

Filed Sept. 3, 1924

Inventor:
F. W. Brown,

by J. S. Mason Atty.

UNITED STATES PATENT OFFICE.

FRED W. BROWN, OF CLEVELAND, OHIO.

DEVICE FOR SEPARATING FRUIT JUICES FROM PULP.

Application filed September 3, 1924. Serial No. 735,595.

To all whom it may concern:

Be it known that I, FRED W. BROWN, a citizen of the United States of America, residing at Cleveland, in the county of Cuyahoga and State of Ohio, have invented a certain new and useful Device for Separating Fruit Juices from Pulp, of which the following is a full, clear, and exact description.

10 This invention relates to devices for extracting the juices from fruits.

Among the objects of the invention are to provide a device of the character referred to which will be capable of permitting the 15 pulp to be removed from the skin by one operation, and to extract the juice from the pulp by straining it, during a second operation. Preferably, the pulp when removed from the rind or skin is permitted to drop 20 into a jar or other receptacle to which the device may be attached, and then such jar or receptacle is tipped slightly to permit the juices to be separated from the pulp by a strainer, said operations being performed 25 neatly and expeditiously, and without spattering. The device is accordingly conducive to the extracting of fruit juices in a sanitary manner, with rapidity, and without the exercise of unnecessary labor.

30 Other objects and advantages of the invention will appear to those skilled in the art from the following description of a preferred construction, the details of which will be understood from said description, in 35 connection with the accompanying drawings, in which,

Fig. 1 is a view, in side elevation, illustrating one form of the invention applied to a fruit jar;

40 Fig. 2 is a plan view;

Fig. 3 is a longitudinal sectional view of the device, showing a portion of the jar to which it is attached, the parts being in position for pouring, and,

45 Fig. 4 is an inverted plan view.

As shown, the device comprises a concave body portion 2, shaped somewhat like a saucer and having a pouring lip 4 at its edge, and a threaded neck 6 for engagement 50 with an external thread surrounding the neck of an ordinary fruit jar, 8, or other receptacle. The central portion of the body 2 is provided with a discharge opening 10, and projecting downwardly at an angle 55 within said opening from the body portion of the device, is a strainer 12, herein shown

as made up of a plurality of spaced, parallel bars, the spaces between the bars being closed at one end by a transverse bar 14. The strainer is provided at each side with 60 a triangular web 16, and such strainer as an entirety, and including the web 16, terminates a distance suitably spaced from the inside surface of the neck of the jar, leaving a space 18, which permits the discharge 65 of the pulp that falls upon the strainer, into the jar or receptacle.

At spaced points around the central discharge opening projecting upwardly from the body, are a plurality of curved bars 20, 70 the same being preferably arranged radially as best shown in Fig. 2. These bars meet at an apex 21, at which point they are preferably curved so as to present a rounded surface. Some of the bars 20 are attached to 75 the body portion 2 of the device and act to support the group of bars, and others, 20^a, are somewhat shorter than the bars which rest upon the body. The bars 20^a preferably are alternatively arranged with the bars 80 20 and the spaces beneath the ends of the bars 20^a permit the fruit pulp to pass freely downwardly upon the strainer 12 and thence into the receptacle 8.

In the operation of the device, an orange, 85 lemon, or other fruit, having preferably been previously separated into suitable parts, is rotated under pressure in contact with the bars 20, 20^a which separates the pulp from the skin and mashes the pulp 90 permitting it to fall down upon the strainer 12, and to pass thence through the space 18 into the receptacle 8. When a suitable amount of the pulp has been thus discharged 95 into the receptacle the latter is tilted at a suitable angle, and the fruit juices are discharged through the strainer 12 and from the body portion 2 of the device out of the spout 4 into a glass or other container. During this pouring process the pulp will 100 be prevented from escaping from the receptacle by the strainer so that the juices which are poured out will be entirely free from any solid matters, such as pulp, seeds, etc.

Changes may be made in the details of 105 construction or in the relative arrangement of the several parts shown without departing from the spirit of the invention.

What I claim is:

1. A device of the character described, 110 comprising a body portion provided with a central discharge, a strainer angularly dis-

posed in said discharge and having an open end portion to permit the pulp to escape therefrom, and means carried by said body and located over said discharge for extracting pulp.

2. A device of the class described, comprising a curved body portion having a central discharge opening and a depending neck for connection to a receptacle, a strainer extending downwardly within said discharge opening at an inclination and arranged to permit the discharge of the pulp within the receptacle, and a plurality of separated bars supported around said discharge opening and meeting at the center of the device.

3. A device of the class described, comprising a curved receptacle having a pouring spout and a central outlet opening, means for attaching said receptacle to a container, a downwardly-inclined strainer extending from said receptacle into its outlet,

said strainer terminating a suitable distance from the side of the container to which the device is attached, and a plurality of radially arranged spaced, pulp-removing arms located above and over the discharge opening of the receptacle.

4. A device of the class described, comprising a curved saucer-shaped receptacle having a pouring spout and a central discharge opening, a neck extending from said receptacle and adapted for attachment to a container, a downwardly-inclined strainer extending across the outlet of said receptacle and terminating a distance from the neck thereof so as to provide a discharge space, and upwardly arched bars supported centrally above the discharge of the container and suitably spaced apart for removing fruit pulp from its skin.

In testimony whereof I have hereunto set my hand this 25th day of August A. D. 1924.

FRED W. BROWN.
